US00D563082S

(12) **United States Design Patent** (10) Patent No.: **US D563,082 S**
Seamans (45) Date of Patent: ** *Mar. 4, 2008

(54) **FOOTWEAR**

(75) Inventor: **Scott Seamans**, Boulder, CO (US)

(73) Assignee: **Crocs, Inc.**, Niwot, CO (US)

(**) Term: **14 Years**

(21) Appl. No.: **29/251,329**

(22) Filed: **Jan. 6, 2006**

(51) LOC (8) Cl. **02-04**

(52) U.S. Cl. **D2/916**

(58) Field of Classification Search .... **D2/916, D2/896, 897, 918, 919, 923, 943, 947-969; 12/142 V; 36/3 R, 4, 10, 9 A, 11.5, 113, 36/45**

See application file for complete search history.

(57) **CLAIM**

The ornamental design for footwear, as shown and described.

DESCRIPTION

FIG. 1 is a front perspective view of footwear, showing my new design;

FIG. 2 is a front view thereof;

FIG. 3 is a back view thereof;

FIG. 4 is a side view thereof;

FIG. 5 is a side view thereof, opposite that shown in FIG. 4;

FIG. 6 is a top view; and,

FIG. 7 is a bottom view.

The broken lines shown are for illustrative purposes only and form no part of the claimed design.
